CLAIM

The ornamental design for an electronic piano, as shown and described.

DESCRIPTION

FIG. 1 is a perspective view of the top, front and left side of an electronic piano showing my new design;

FIG. 2 is a front elevational view thereof;

FIG. 3 is a top plan view thereof;

FIG. 4 is a left side elevational view thereof, the right side elevational view being a mirror image;

FIG. 5 is a rear elevational view thereof;

FIG. 6 is a bottom plan view thereof;

FIG. 7 is a front elevational view thereof, with the cover in the closed position;

FIG. 8 is a top plan view thereof with a cover in a closed position; and,

FIG. 9 is a right side elevational view thereof with the cover in the closed position, the left side elevational view being a mirror image.
